(57) **CLAIM**

The ornamental design for a desk, as shown and described.

DESCRIPTION

FIG. 1 is a perspective view of a desk showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and

FIG. 7 is a bottom plan view thereof;

FIG. 8 is a partial enlarged view of portion 8 shown in FIG. 2;

FIG. 9 is a partial enlarged view of portion 9 shown in FIG. 3;

FIG. 10 is a partial enlarged view of portion 10 shown in FIG. 4;

FIG. 11 is a partial enlarged view of portion 11 shown in FIG. 5; and,

FIG. 12 is a partial enlarged view of portion 12 shown in FIG. 7.

The broken lines depict portions of the desk and form no part of the claimed design.

1 Claim, 12 Drawing Sheets
